UNITED STATES PATENT OFFICE.

WILLIAM W. MACFARLANE, OF ELKINS PARK, PENNSYLVANIA, ASSIGNOR TO MACFARLANE COMMUNICATIONS CORPORATION, OF NEW YORK, N. Y., A CORPORATION OF NEW YORK.

TRAIN TELEPHONE SYSTEM.

Application filed April 9, 1920. Serial No. 372,440.

To all whom it may concern:

Be it known that I, WILLIAM W. MACFARLANE, a citizen of the United States, and a resident of Elkins Park, in the county of 5 Montgomery, in the State of Pennsylvania, have invented a certain new and useful Improvement in Train Telephone Systems, of which the following is a specification.

The present invention relates generally 10 to systems of train control and is more particularly an improvement on the invention disclosed in application Ser. No. 203378, filed Nov. 22, 1917, now Patent No. 1,389,258.

The main object of the invention is to dispense with the necessity of having a constant 15 current flow in the rails.

The invention consists, broadly, in the provision of a normally incomplete circuit so connected with the line wires and with the 20 traffic rails that it does not bridge the rails, whereby, when a car enters a block or subdivision of the rails, communication is established between the car and a wayside station.

25 Other features will appear as the specification proceeds:

In the accompanying drawings the invention is disclosed in several concrete and preferred forms in which

30 Fig. 1 is a diagrammatic view of a system showing one form of the invention.

Fig. 2 is a diagrammatic view of a system showing a modified form of the invention.

1 and 2 indicate line wires and 3 is an 35 auxiliary wire all paralleling the traffic rails 4 and 5. Wayside stations or central offices 6 are connected with line wires 1 and 2 at suitable intervals, say, of one hundred miles. One rail (4) of the traffic track is 40 divided by suitable insulation (7) into blocks or sections of suitable length, depending upon the traffic conditions and other circumstances, as will be understood. 8 and 9 indicate two conductors connected with the 45 line wires, 1 and 2, and with rails 4 and 5. A shunt (10) is connected between 8 and 9, said shunt being normally ruptured by armature 11 under the control of magnet 12. Magnet 12 constitutes the core of a transformer winding 13 in inductive relation to winding 14 of conductor 15. Said conductor 50 15 is a part of a normally complete circuit formed by conductors 15, rail 5, conductor 16 and conductor 3. 17 indicates a car hav-

ing a winding 18 (which is disclosed in said 55 Patent No. 1,389,258 has an extremely low resistance) in circuit with rail 5, and in inductive relation to telephone circuit 19, having battery 20. The wayside station has a local circuit that may be traced as follows: 60

From battery 21 by way of transmitter 22, conductor 23, key 24 (when depressed), conductor 25, transformer winding 26 and conductor 27 back to battery 21. The alternating speech current set up in transformer 65 winding 26 induces a similar current in transformer winding 28, and then flows by way of conductor 29, line wire 2, conductor 9, having transformer winding 13 to rail 4, across car 17 to rail 5, by way of conductor 70 8, line wire 1, conductor 30 to key 31, and by way of conductor 32 back to transformer 28. Energization of transformer coil 13 induces a current in coil 14 which flows by way of conductor 15, rail 5, winding 18 on car, conductor 16 and auxiliary wire 3 back to winding 14. This induces a current in local telephone circuit 19 of the car. The foregoing description of the circuits assumes that the train is traveling from right to left and is in 80 advance of conductor 16 and behind conductor 15, but it will be evident that if the train is in advance of conductor 15 and behind conductor 16, then current flows to or from winding 18 of the train between the conductor 85 15 in rear of the train and the conductor 16 in front of the train. A speech current generated in the car will be transmitted to the line wire and coil 28 over the circuits previously described, and, button 24 being now 90 elevated, current will pass from the coil 28 to receiver 33 as follows:

From coil 26 by wire 34 including receiver 33 to button 24, and thence by conductor 95 25 back to coil 26.

To give a signal, either audible or visual or both, along the line of way, means are employed for energizing core 12 sufficiently to attract armature 11 thereby closing shunt 10 and illuminating light 35 and ringing bell 36. This is accomplished by depressing key 31, thereby placing a powerful source of current here shown as a battery 21 in circuit with line wires 1 and 2, and establishing a circuit as follows:

From battery 21 to key 31, conductor 30 to line wire 1, by way of conductor 8, rail 5, car 17, rail 4, conductor 9 and coil 13 to line

wire 2, and by wire 37 back to battery 21. As previously pointed out, this attracts armature 11 and closes shunt 10. In addition, it will be understood, that car 17 may communicate over the line wires with car 17^a in another block or with another car of the same train, but in another block.

As a modification of the invention, auxiliary wire 3 may be omitted, by grounding wire 15 and rail 5, as shown in Fig. 2.

I claim:

1. A system of the character described comprising: line wires, traffic rails, a source of supply for impressing current on the line wires, a normally incomplete circuit connected to the line wires and connected to but not bridging the rails, a second and normally complete circuit connected to the same traffic rail, transformers in said circuits in inductive relation to each other, a car for completing said first-named circuit by bridging the rails, and means on the car responsive to current in the second circuit.

2. A system of the character described comprising: a wayside station including sending and receiving devices, line wires, traffic rails, a normally incomplete circuit connected to the line wires and connected to but not bridging the rails, a second and normally complete circuit connected to the same traffic rail, transformers in said circuits in inductive relation to each other, a car for completing said first-named circuit by bridging the rails, and sending and receiving devices on the car in circuit with the track.

3. A system of the character described comprising: line wires, traffic rails, a source of supply for impressing current on the line wires, a normally incomplete circuit connected to the line wires and connected but not bridging the traffic rails, a car for completing the circuit by bridging the rails, and means on the car responsive to the current in the rails, a normally open shunt including an armature in said circuit, a magnet in said circuit controlling said armature, and means for sending an impulse through said circuit to energize said magnet, and a signal along the line of way controlled by said shunt.

4. A system of the character described comprising: a wayside station including sending and receiving devices, line wires, traffic rails, a normally incomplete circuit connected to the line wires and connected to but not bridging the traffic rails, a car for completing the circuit by bridging the rails, and sending and receiving devices on the car in circuit with the track, a normally open shunt including an armature in said circuit, a magnet in said circuit con-

trolling said armature, and means for sending an impulse through said circuit to energize said magnet.

5. A system of the character described comprising: a wayside station including sending and receiving devices, line wires, traffic rails, a normally incomplete circuit connected to the line wires and connected to but not bridging the traffic rails, a car for completing the circuit by bridging the rails, and sending and receiving devices on the car in circuit with the track, a normally open shunt including an armature in said circuit, a magnet in said circuit controlling said armature, and means for sending an impulse through said circuit to energize said magnet, and a signal along the line of way controlled by said shunt.

6. A system of the character described comprising: line wires, traffic rails, a source of supply for impressing current on the line wires, a normally incomplete circuit connected to the line wires and connected to but not bridging the rails, a second and normally complete circuit connected to the same traffic rail, a normally open shunt in said first circuit, transformers in said circuits in inductive relation to each other, one of said transformers constituting a magnet, an armature in said shunt under the control of said magnet, a car for completing said first named circuit by bridging the rails, and means on the car responsive to current in the second circuit, and a second means for impressing a current of sufficient value on the line wires to energize the magnet.

7. A system of the character described, line wires, traffic rails, a normally incomplete circuit connected to the line wires and connected to but not bridging the rails, a second and normally complete circuit connected to the same traffic rail, a normally open shunt in said first circuit, transformers in said circuits, in inductive relation to each other one of said transformers constituting a magnet, an armature in said shunt under the control of said magnet, a car for completing said first-named circuit by bridging the rails, sending and receiving devices on the car in circuit with the track, a wayside station including sending and receiving devices connected to the line wires, means for impressing a current of sufficient value on the line wires to energize the magnet, and a wayside signal under the control of the shunt.

Signed at the borough of Manhattan, in the county of New York and State of New York, this seventh day of April, 1920.

WILLIAM W. MACFARLANE.
